US00D764451S

(12) **United States Design Patent**
Hung et al.

(10) **Patent No.:** **US D764,451 S**
(45) **Date of Patent:** **** Aug. 23, 2016**

(54) **COVER FOR PORTABLE ELECTRONIC DEVICE**

(71) Applicant: **Acer Inc.**, New Taipei (TW)

(72) Inventors: **Li-Chi Hung**, New Taipei (TW);
Yen-Chiu Hsu, New Taipei (TW);
Hung-Yang Huang, New Taipei (TW)

(73) Assignee: **Acer Inc.**, New Taipei (TW)

(**) Term: **14 Years**

(21) Appl. No.: **29/508,664**

(22) Filed: **Nov. 10, 2014**

(30) **Foreign Application Priority Data**

Jun. 10, 2014 (TW) 103303481

(51) **LOC (10) Cl.** **14-03**

(52) **U.S. Cl.**

(57) **CLAIM**

The ornamental design for a cover for portable electronic device, as shown and described.

DESCRIPTION

FIG. 1 is a rear perspective view of a cover for portable electronic device showing our new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a rear perspective view thereof shown in a state of use with a portable electronic device shown in broken lines; and,

FIG. 9 is a front perspective view thereof.

The broken lines depict a portable electronic device and portions of the cover that form no part of the claimed design.

1 Claim, 7 Drawing Sheets
